OTHER PUBLICATIONS

Stanley Heavy-duty electric pencil sharpener, as shown on www.amazon.com, dated Apr. 3, 2006 (2 pages).*

Primary Examiner—Elizabeth A. Albert*Assistant Examiner*—Karen E Eldridge Powers(74) *Attorney, Agent, or Firm*—Brinks Hofer Gilson & Lione(57) **CLAIM**

We claim the ornamental design for a pencil sharpener, as shown and described.

DESCRIPTION

FIG. 1 is a front perspective view of a pencil sharpener of the present invention;

FIG. 2 is a front view thereof;

FIG. 3 is a first side view thereof;

FIG. 4 is a second side view thereof;

FIG. 5 is a top view thereof;

FIG. 6 is a rear view thereof;

FIG. 7 is a bottom view thereof; and,

FIG. 8 is a rear perspective view thereof.
